UNITED STATES PATENT OFFICE.

RAYMOND C. PARENT, OF LOS ANGELES, CALIFORNIA, ASSIGNOR OF ONE-HALF TO
JAMES C. WILLARD, OF LOS ANGELES, CALIFORNIA.

GAME.

Application filed July 11, 1927. Serial No. 204,805.

My invention is a game simulating billiards or pool, or games of the same type and using as a cue, a device representing a gun.

5 An object of my invention is the construction of a game played in the manner of billiards, pool or similar games, having a rotatable table or game board so that the players may remain stationary and seated if 10 desired, turning the table to play the game.

Another object of my invention is in a game similar to billiards, pool or the like, to strike the balls by a cue, using a spring actuated gun to give the striking blow with 15 the cue.

In constructing my invention, the game board or table has a suitable flat surface to allow rolling of the balls, and with an edge or rim constructed in the same manner as 20 billiard or pool tables with a rubber pad or the like. Also, there are pockets provided in the margin of the table. This table is mounted on a turn table structure or stand to allow rotation so that the players may 25 turn the table to a convenient position for striking the balls, and if desired, the players may remain stationary instead of having to move around the table.

In the construction of the cue, I have a 30 device simulating a rifle in shape, with a slideable bar which may be termed a "cue." This bar has a trigger thereon and is actuated by spring power. A simple contrivance for actuating the cue is to have an 35 elastic band with one end secured to the rear end of the cue which extends through the barrel of the gun, and the other end secured to the barrel part of the gun structure. Therefore, on pulling back on the trigger, 40 the band is stretched, and on release, the cue is shot forward, there being a limit to the movement of the cue, and thus giving the striking force against the balls.

45 My invention is illustrated in the accompanying drawings in which:

Figure 1 is a perspective view of the game board with the gun operating the cue resting thereon.

50 Fig. 2 is a longitudinal section of the board.

Fig. 3 is a side elevation of the gun having the cue therein.

Fig. 4 is a longitudinal vertical section through the gun.

Fig. 5 is a side elevation of a pistol type device having a cue.

The table part of my game is constructed as follows: A suitable substantial base 11 is employed which may rest on an ordinary table top indicated by 12. This base preferably has a recess 13 at the center, and also an upper recess 14. A central block 15 is attached to the base, there being a pivot bolt 16 which extends through the center of the base having its head fitting in the recess 13, and may have a washer 17 if desired, or some arrangement forming a wearing bearing. If desired, there may be a bushing 18 surrounding the bolt, this bolt being secured in a lug 19 depending from the block 15 and fitting in the recess 14.

The table or game board proper 20, is secured to the block 15 by screws 21 or the like. This board has a suitable padding on its upper surface 22, and has a rim 23 with rubber bumpers or deflectors 24. There are also a series of pockets 25 formed by openings in the rim, with bags 26 to catch balls indicated by 27 which are in the pockets.

The gun structure designated by the numeral 28 has a stock 29 with a barrel section 30 connected thereto, the barrel having a longitudinal bore 31 through the barrel from end to end, and there is a lateral slot 32 through the stock into the bore of the 85 barrel.

The cue 33 is constructed of a rod which fits in the bore 31, this having a striking head 34 with a trigger 35 which extends through the slot 32, this trigger having a finger grip 36 below the upper part of the stock. The rear end 37 of this rod forms the cue and extends beyond the rear end of the barrel and has a pin 38 or the like connected thereto. A rubber, or other elastic 90 band 39 is connected to this pin and is stretched along the barrel of the gun structure, being secured thereto by a fastening 40 or the like.

95 The manner of playing the game is substantially as follows: The balls used are miniature billiard balls or proper sized marbles, and these are placed on the playing table, which table may be rotated as above described. There is a certain frictional resistance to the rotation of the table sufficient to prevent rapid spinning which would 100 displace the balls by centrifugal action, and 105

the base is of sufficient weight so that the table will not tilt in being turned or manipulated. It is intended however, that the players do not rest their weight on the table.

5 In manipulating the gun to strike the balls with the cue, the trigger is pulled rearwardly in the stop 32 by the finger, and the player may thrust the stop of the gun against his shoulder if desired, and take an 10 aim at the ball to be struck and in the direction it is to be struck. If it is desired to give a hard blow, the trigger may be drawn back the full extent of the slot and then released, and by proper judgment in striking 15 the ball, a relatively heavy blow may be given. If it is desired only to have a light blow, the trigger will only be partly drawn back and released with the elastic only partly tensioned, and thus give a light 20 blow. It is apparent that the players may manipulate the gun and the position in which they strike the balls so as to practically secure the effect of playing billiards or pool with ordinary cues, but remain stationary and move the table.

25 In Fig. 5 I show a pistol type of device for operating a cue, this having a pistol handle grip 41 with a barrel 42 and having a slot 43 in the stock to accommodate the 30 trigger of the rod forming the cue. The construction and operation of the pistol device is the same as the gun type of device shown in Figs. 3 and 4. If desired a person may aim the barrel of the pistol by handling 35 it in one hand while the grip 41 of the pistol is held in the other hand; whereas, with

the gun the player aims by placing the end of the stock against the shoulder.

In playing the above mentioned game with my game board, it will be seen that it affords 40 a game of skill in being able to aim the gun correctly and also using judgment in the striking of the balls. It is apparent, however, that if desired the gun or the pistol type of device with the cue may be used 45 with a stationary billiard table or the like, the player moving around the table to play the game.

Various changes may be made in the principles of my invention without departing 50 from the spirit thereof, as set forth in the description, drawings and claim.

I claim:—

In a game, a striking implement comprising 55 a gun-like structure having a barrel with a longitudinal bore, a stock connected thereto having a lateral slot entering the said bore, a rod slideable in the bore and extending therethrough forming a cue, a trigger rigidly connected to the rod and extending through 60 the slot, a spring connected to the barrel and to the rod, the slot forming a limiting movement in both directions for the trigger, thereby giving a limit to the projection of the rod and to the tension of the spring, the 65 trigger and rod being adapted for retention in a retracted position solely by engagement with a person's finger.

In testimony whereof I have signed my name to this specification.

RAYMOND C. PARENT.
